UNITED STATES PATENT OFFICE.

HORACE BOYLSTON DUMMER, OF NEW YORK, N. Y.

TOY AEROPLANE.

1,327,530.

Specification of Letters Patent.

Patented Jan. 6, 1920.

Application filed September 23, 1919. Serial No. 325,754.

To all whom it may concern:

Be it known that I, HORACE BOYLSTON DUMMER, a citizen of the United States, and a resident of the city of New York, borough 5 of Manhattan, in the county and State of New York, have invented a new and Improved Toy-Aeroplane, of which the following is a full, clear, and exact description.

This invention relates to new and useful 10 improvements in toys, and it pertains more particularly to a toy imitation of an aeroplane.

The primary object of the invention is to provide a body which is in simulation of an 15 aeroplane fuselage, said body being so constructed as to carry a book, pamphlet, or the like, which serves as the sustaining plane for the body.

A further object of the invention is to 20 provide a device of this character in which the pamphlet serving as the plane may be readily removed.

A still further object of the invention is to 25 provide a toy which will be capable of sustaining itself in guiding flight, the impetus being furnished by the operation in the manner commonly employed with darts.

With the above and other objects in view, 30 reference is had to the accompanying drawings, in which—

Figure 1 is a side elevation of a toy constructed in accordance with the present invention;

Fig. 2 is a top plan view thereof;

Fig. 3 is a detail view in elevation of the 35 forward portion of the body with the sustaining plane removed;

Fig. 4 is a detail perspective view of the sustaining plane.

Referring more particularly to the drawings, the device comprises a body 5, formed 40 of a single piece of material, such as cardboard, thin wood, or the like, and said body is so formed as to provide a projection 6 at the forward end in imitation of the landing 45 chassis of an aeroplane. At the extreme forward end of the body 5, an imitation propeller 7 is formed, while at the extreme rear end, an imitation rudder 8 is provided. The 50 reference character 9 designates a projection in imitation of the tail skid commonly employed. It is to be understood that each of the aforementioned elements is formed integral with the body 5.

Referring to Fig. 3, it will be seen that

the body 5 is provided with an elongated slot 10, the said slot being angularly disposed with respect to the longitudinal axis of said body and extending entirely there-through.

The reference character 11 designates a sustaining plane, which in the present instance, is in the form of a pamphlet, having cover sections 12 with bent-in leaves 13. These leaves are adapted to contain any suitable reading matter and are adapted to give sufficient thickness to the sustaining plane 11 to cause the same to frictionally engage the defining edges of the elongated slot 10 in order that it will be removably retained in said slot. Owing to the angular disposition of the slot 10, it will be apparent that the sustaining plane 11 will be angularly disposed with respect to the body 5, in such a manner as to cause the same to rise when 70 thrown by the operator, thus causing the same to glide in flight under the impetus given by the throwing operation.

By this construction, it will be seen that in addition to the device being used as a toy, 80 it may be used as means for distributing circulars or other advertising matter, and that if the same be thrown from suitable height, such as from the roofs of tall buildings, the device will glide great distances, thus providing a means for a wide distribution of advertising matter.

I claim:

1. A device of the character described comprising a body portion provided with an 90 angularly disposed slot, and a sustaining plane in the form of a pamphlet having covers and leaves, said pamphlet being removably maintained within said angularly disposed slot by frictional engagement with 95 the defining edges thereof.

2. A device of the character described comprising a relatively thin sheet of material cut in imitation of an aeroplane fuselage and its associated elements, said fuselage being provided near its forward end with an angularly disposed slot having closed ends and a sustaining plane, said sustaining plane being of a width equal to the length of said slot and of a thickness slightly 100 greater than the width of said slot whereby the sustaining plane is maintained in position within the slot by a frictional engagement with the defining edges thereof.

HORACE BOYLSTON DUMMER.
